UNITED STATES PATENT OFFICE.

JOHN J. TONER, OF NEW YORK, N. Y.

RUDDER.

Application filed June 7, 1922. Serial No. 566,561.

To all whom it may concern:

Be it known that I, JOHN J. TONER, a citizen of the United States, and a resident of the city of New York, borough of Manhattan, in the county and State of New York, have invented new and useful Improvements in Rudders, of which the following is a full, clear, and exact description.

This invention relates to rudders for use in the navigation of screw propelled vessels.

In the art of navigation great attention has been directed to the development of devices that facilitate the manuevering of vessels. For ordinary purposes devices which give navigators great control of their vessels are valuable in that they decrease the danger of loss of vessels venturing into unknown harbors and sailing in busy waterways. When we consider the art of naval warfare the capacity of manuevering is of extreme importance and so devices that give great control of war vessels are in demand.

The general object of this invention is the provision of a simple and efficient rudder for use in conjunction with vessels that may be operated to decrease the speed of the vessel and to serve as a reversing device.

This object is accomplished by mounting a rigid casing, open at both ends, in alignment with the screw propeller, and, associating with the casing, means for closing the passage through the same so as to convert the rudder into a reversing device.

This and other objects of the invention will be more clearly understood from the following detailed description and accompanying drawings, in which—

Figure 1 is a side elevation of the stern of a vessel showing a section of the rudder; Figure 2 is a section on the line 2—2, Figure 1;

Figure 3 is a section along the line 3—3, Figure 1;

Figure 4 is a top plan view of a horizontal section of a modified form of the rudder; and

Figure 5 is a section along the line 5—5, Figure 4.

Referring to the above-mentioned drawings, a vessel 10 is shown provided with a screw propeller 11 mounted on the driving shaft 12. Extending rearward from the bottom of the vessel is a skag 13. Rotatably mounted in the bearing 14 attached to the ship is a hollow rudder post 15 to which the rudder assemblage 16 is attached. The rudder assemblage consists of a U-shaped plate 17 having a plate 18 attached to its lower edges, as shown in Figure 3. Hinged to the plate 17 at 19 is a plate 20. Extending from a lug 21 attached to the plate 20 is a chain 22 which is guided by the roller 23 into the hollow post 15. Mounted on the top of the vessel is a roller 24 over which the chain 22 passes. The plate 18 has a pintle 25 attached thereto which is mounted in a bearing formed in the skag 13.

When the vessel is in operation and progressing forward, its course may be guided by means of the rudder 16, which consists of a casing open at both ends, the casing being constructed from the plates 17 and 18. The rudder may be rotated about the vertical rudder post by any well known means such as those commonly used with vessels. The water acted upon by the screw propeller 11 is forced through the rudder 16. If it is desired to delay the movement of the ship, the plate 20 is raised by means of the chain 22. When the rudder is closed by means of the plate 20, if it has been properly designed the action of the water upon the same as it is forced backward by the screw propeller 11 will cause the ship to stop and finally to move astern.

The rudder described in the preceding paragraphs may be made in many different shapes and many different devices may be provided for closing it. A modified form is shown in Figures 4 and 5. In this case the rudder consists of a cylindrical casing 26, open at both ends, mounted in alignment with the screw propeller 11. It is supported by the hollow rudder post 15 and the skag 13. Two semicircular gates 27 and 28 are mounted in the casing 26, one supported by a sleeve 29 rotatably mounted in the hollow post 15 and the other by a shaft 30 rotatably mounted in the sleeve 29. These gates 27 and 28 may be operated by means of tillers attached to the sleeve 29 and the shaft 30. Other means might be provided for operating the same but as this is no part of the invention it will not be set forth in detail.

The operation of this modification is the same as that of the preferred form described above.

I would state in conclusion that while the illustrated examples constitute practical embodiments of my invention, I do not limit myself strictly to the exact details herein illustrated since manifestly the same can be

considerably varied without departing from the spirit of the invention as defined in the appended claims.

Claims.

5. 1. In combination with a ship including a propeller and a hollow rudder post, a rudder of the character described comprising a casing open at both ends fixed to the rudder post in alignment with the propeller, 10 said rudder post being mounted for rotation about a vertical axis, members rotatably mounted in the hollow rudder post and extending into the casing, gates attached to said rotatably mounted members, and means

for operating the rotatably mounted members to operate the gates to close the casing.

2. In combination with a ship including a screw propeller and a hollow rudder post, a rudder of the class described comprising a cylindrical casing open at both ends attached to the rudder post in alignment with the propeller, a sleeve rotatably mounted in the rudder post and a post rotatably mounted in said sleeve, and a gate attached to the sleeve and another gate to the post 20 mounted in the sleeve and operated upon the operation of the sleeve and post.

JOHN J. TONER.
